(57) **CLAIM**

The ornamental design for a compact multi-function LED lighthead, as shown and described.

DESCRIPTION

FIG. 1 is a top perspective view of a compact multi-function LED lighthead showing my new design;

FIG. 2 is a bottom perspective view thereof;

FIG. 3 is a front view thereof;

FIG. 4 is a top plan view thereof;

FIG. 5 a bottom plan view thereof; and,

FIG. 6 is a right side view, the opposite left side view being a mirror image thereof.

No claim is made to the rear view. The broken lines shown in the drawings illustrate environmental subject matter which form no part of the claimed design.
